UNITED STATES PATENT OFFICE

2,494,426

AMPLIFIER WITH NEGATIVE FEEDBACK

Hugo Gerrit Beljers, Willem Six, and Jan te Winkel, Eindhoven, Netherlands, assignors to Hartford National Bank and Trust Company, Hartford, Conn., as trustee

Application July 2, 1946, Serial No. 680,890
In the Netherlands March 4, 1943

Section 1, Public Law 690, August 8, 1946
Patent expires March 4, 1963

2 Claims. (Cl. 179—171)

1. This invention relates to an amplifier with negative feedback the amplification of which is variable with frequency. The desired variation of amplification with frequency may be obtained in known manner by including in the negative feedback circuit a network the transmission factor β of which in respect of its magnitude exhibits a variability with frequency reciprocal to that of the desired amplification. In fact, for the amplification μ' of an amplifier with negative feedback there applies the formula

$$\mu' = \frac{\mu}{1 + \mu\beta}$$

in which μ represents the amplification without negative feedback which for $\mu\beta \gg 1$ changes to

$$\mu' = \frac{1}{\beta}$$

from which it appears that the amplification μ' is reciprocal to the transmission factor β of the network in the negative feedback circuit. Consequently, by constituting this network in a suitable manner it is possible to obtain any desired variation of amplification with frequency. However, the network will also produce a phase displacement variable with frequency in the negative feedback circuit and this detrimentally affects the stability of the amplifier, since in definite frequency ranges the negative feedback changes to positive feedback with the danger involved for self-oscillating of the amplifier.

The present invention purports to provide steps whereby the detrimental influence of the network in the negative feedback circuit upon the phase displacement of the negative feedback voltage is avoided.

According to the invention, this object is achieved by including a network in the output circuit of an amplifying tube of the amplifier, which network is constituted in such manner that the amplification factor β_1 of the amplifying tube and the network together substantially satisfies the relation $\beta\beta_1 = \text{constant}$ and real.

In order that the invention may be more clearly understood and readily carried into effect, it will now be described more fully by reference to the accompanying drawing.

Figure 1 shows a diagram of the principle of an amplifier according to the invention. This amplifier comprises an amplifying tube 1 coupled to output terminals 4, 5 through a network 2 and an amplifier 3. The voltage e_1 to be amplified is supplied to input terminals 6, 7. The input circuit has also supplied to it a negative feedback voltage e_k which is derived, through a network 55

8, from the output terminals of the amplifier between which the output voltage e_3 is set up. The amplification factor of the amplifying tube 1 and the network 2 without negative feedback, that is to say the relation which exists between the voltage e_2 and the voltage e between the grid and the cathode of the amplifying tube 1 is assumed as β_1 and the amplification factor of the amplifier 3

$$\frac{e_3}{e_2} \text{ as } \mu$$

Consequently

$$e_k = \frac{\mu\beta\beta_1}{1 + \mu\beta\beta_1} e_1$$

Now, according to the invention, the networks 2 and 8 are constituted in such manner that $\beta\beta_1 = k = \text{constant}$ and real, so that the above-mentioned relation changes to

$$e_k = \frac{\mu k}{1 + \mu k} e_1$$

from which it follows that the phase displacement of the negative feedback voltage e_k relatively to the input voltage e_1 is invariable with the properties of the network 8. It will now always be possible for $\beta\beta_1$ to be made exactly constant. A very small phase displacement is already obtained, if $\beta\beta_1$ is maintained constant as far as possible.

20. In Figure 2 an impedance Z_1 is substituted for the network 2 shown in Figure 1 and an impedance Z_3 for the network 8. In series with Z_3 is connected, in addition, an impedance Z_2 . Z_2 and Z_3 are constituted by impedances Z_2' and Z_3' , respectively, which are shunted by a resistance R .

For the negative feedback voltage e_k applies, as before,

$$e_k = \frac{\mu\beta\beta_1}{1 + \mu\beta\beta_1} e_1$$

40. With

$$\beta_1 = \frac{e^2}{e} = S Z_1$$

wherein S represents the mutual conductance of the amplifying tube and wherein it is assumed that the internal resistance is high relatively to Z_1 and

$$\beta = \frac{Z_3}{Z_2 + Z_3}$$

50. this expression may read:

$$e_k = \frac{\mu S \frac{Z_1 Z_3}{Z_2 + Z_3}}{1 + \mu S \frac{Z_1 Z_3}{Z_2 + Z_3}} e_1$$

3

As before, between e_k and e_1 there exists a phase relation independent on the network in the negative feedback circuit, if the product $\beta\beta_1$ is constant. Since

$$\beta\beta_1 = S \frac{Z_1 Z_3}{Z_2 + Z_3}$$

this will be the case if

$$\begin{aligned} Z_1 Z_3 &= \text{constant} \\ Z_2 + Z_3 &= \text{constant} \end{aligned}$$

$Z_1 Z_3 = \text{constant}$ implies that the impedances Z_1 and Z_3 must be inverse.

The second condition $Z_2 + Z_3 = \text{constant}$ may be fulfilled by constituting Z_2 and Z_3 in the manner shown in Figure 2, thus satisfying the condition $Z_2' Z_3' = R^2$. In fact,

$$\begin{aligned} Z_2 + Z_3 &= \frac{Z_2' R}{Z_2' + R} + \frac{Z_3' R}{Z_3' + R} - \\ &\quad \frac{2Z_2' Z_3' R + (Z_2' + Z_3') R^2}{Z_2' Z_3' + (Z_2' + Z_3') R + R^2} = R \end{aligned}$$

It will not always be possible to fulfill exactly the condition $Z_1 Z_3$, since Z_3 comprises the parallel resistance R , which makes it necessary for Z_1 to comprise a series-resistance. Now, Z_1 comprises also the capacity which exists between the anode and the cathode of the amplifying tube and with this no resistance can be connected in series. However, the phase displacement resulting from this inaccuracy is small. The condition $Z_2 + Z_3 = \text{constant}$ may alternatively be satisfied by replacing Z_2 by a resistance R' which is high relatively to the impedance Z_3 . In this case the resistance R parallel to Z_3' may be omitted:

What we claim is:

1. An amplifying system for electrical oscillations comprising a first amplifying stage including an electron discharge tube provided with a cathode, a grid and an anode and an output impedance Z_1 connected between said anode and

4

cathode and having a value which is low relative to the internal resistance of said tube, a second amplifying stage whose input is connected across said output impedance of said first stage, and a negative feedback network having a transmission factor variable with frequency, said network including a first negative feedback impedance Z_2 connected across the output of said second stage and a second negative feedback impedance Z_3 interposed in series between the output of said second stage and said first feedback impedance, and means to apply said electrical oscillations in series with the feedback wave developed across said first feedback impedance as an input to the grid of said tube, said impedances having respective values substantially satisfying the relations $Z_1 Z_3 = \text{constant}$, and $Z_2 + Z_3 = \text{constant}$.

2. An arrangement as set forth in claim 1 wherein impedance Z_3 is constituted by the parallel connection of an impedance having a value Z_2' and a first resistance having a value R , and wherein impedance Z_3 is constituted by an impedance having a value Z_3' and a second resistance also having a value R , the respective values of impedances Z_2' and Z_3' substantially satisfying the relation $Z_2' Z_3' = R^2$.
